Louis M. Sanders ATTORNEYS.

UNITED STATES PATENT OFFICE.

EARL H. ROLLINSON, OF LYONS FARMS, NEW JERSEY.

DRY BATTERY.

1,284,458.

Specification of Letters Patent. Patented Nov. 12, 1918.

Application filed August 3, 1917. Serial No. 184,188.

To all whom it may concern:

Be it known that I, EARL HOYT ROLLINSON, a citizen of the United States, residing at Lyons Farms, county of Essex, and State 5 of New Jersey, have invented a new and useful Improvement in Dry Batteries, of which the following is a specification.

It is well known that the modern dry cell battery deteriorates with age and quickly 10 weakens when in use, and that after a period of rest, it will recuperate. Attempts have been made to mix with the depolarizing agent, an electrolyte; but this method has not proved satisfactory, with the result, that in 15 many cases the cells are discarded, because they are thought to be completely exhausted, while in fact the cell only needs electrolyte of correct strength to start the chemical action again.

20 Manufacturers of dry cells have somewhat standardized the construction of the cell, in the following particulars: The body of the container or anode is of sheet zinc rolled into tubular form, with a shallow cup-shaped disk set into the bottom and soldered in place. The container is lined with absorbent paper and saturated with the exciting electrolyte. The carbon electrode or cathode is in the center of the cell, and 25 rounded with the depolarizing agent. The surface of the depolarizer is then covered with a layer of sand and a resinous wax is melted and poured over the surface of the sand to the top of the container to keep it 30 air tight in order to prevent evaporation of the electrolyte as much as possible. The container is then incased in a strawboard tube, when it is ready for use.

In my prior application Ser. No. 171,802, 40 filed May 29th, 1917, I have set forth reasons why cells of the type just described may be given longer life, if inverted when in use and I have there described an improved form of battery holder, in which the 45 cells are normally supported for use in inverted position. The said battery holder, and the above described cell, are admirably adapted for use in connection with my present improvement, which consists in perforating the shallow cup-shaped bottom of the container, placing therein an exciting agent such as sal-ammoniac, (ammonium chlorid), and providing a cover for the cell-bottom. When saturated with water the 50 salt solution trickles through the perforations and is absorbed by the blotting paper

lining where it serves as an effective exciting electrolyte. Actual tests show that the life of a cell may be lengthened 50% or more.

In carrying out my invention I make use of the devices and structures set forth in the following detailed description, and illustrated in the accompanying drawings, 60 wherein:

Figure 1, is a side elevation partly in section of a pair of cells mounted in a battery holder similar to that described in my prior application, above referred to.

Fig. 2, is a section of another form.

Fig. 3, is a plan of a cell bottom, perforated for use in connection with my improvement.

Figs. 4, and 5, are respectively, plan views of the cover and capsule, illustrated in 75 Fig. 2.

Similar reference numerals refer to like parts throughout the description and drawings.

The cells 1, are the usual standard construction having the zinc container made up of the tube 2, into which the cup-shaped bottom 3, is soldered. The container is lined with blotting paper 4, and filled with the depolarizer 5, such as manganese dioxid with 80 the carbon electrode 6, embedded in the center. The cup-shaped bottom 3 is perforated as at 7, and filled with the electrolyte solution 8. The cover 9, is then placed over the bottom of the cell, and which is placed 85 in inverted position, as shown, into the aperture 10, of the battery holder 11, with the electrodes 12, and 13, connected to the connector strips 14, and 15, respectively, which are secured to the under face of the holder 90 11, by means of the screws 16. When the electrolyte solution has become exhausted from the cup-shaped bottom of the cell, it may be replenished. The saturated solution 95 of the exciting electrolyte trickles through the apertures 7, and is absorbed by the blotting paper lining 4, which serves to distribute it through the cell. The apertures 7, together with the aperture 17, in the cover afford a vent for gases generated in the cell 100 when in use, and therefore serve to prevent the swelling and occasional bursting of the walls of the cell, where it is otherwise hermetically sealed.

The improvement as thus far described is 110 the form preferred, when the cell is completed as shown, at the factory with the ex-

citing electrolyte in place. But where the electrolyte is to be applied to cells already in use, I prefer to place the electrolyte in a capsule which may be securely fixed to the bottom of the cell. Such a capsule is illustrated in Figs. 3, 4, and 5, and consists of the cup-member 19, having the circular corrugation 20, in the bottom thereof, with a plurality of apertures 21, therethrough; the 10 corrugation 20, forms a channel for conducting the salt solution to the apertures 7, in the bottom of the cell. The cover 22, fits over the cup-shaped member 19, and is provided with an offset annular flange 23, to 15 engage the bottom of the cell, and hold the entire capsule in place. The cover is provided with an aperture 24, for the escape of battery gases. The capsule with its contents either in granular or compressed tablet 20 form, can be cheaply manufactured, and sold for a nominal price to be applied to cells already in use; when put in use, water is added to the contents of the capsule.

If desired, the cup-member and cover may 25 be permanently secured together with the electrolyte therein, ready to be affixed to the bottom of a cell. To saturate the contents, the capsule may be immersed in water for a few moments, and it may then be applied 30 to the cell as described.

In practice the cup will be nearly filled with a dry granulated sal ammoniac powder, or a compressed tablet of sal ammoniac. Water is then poured over the powder, or 35 tablet, as the case may be, until it is completely saturated, when the covering may be replaced and the capsule applied to the bottom of the cell, as above described. The capsule is of such capacity that it holds the 40 proper amount of water to make a saturated solution of the electrolyte.

It will be understood that different means may be employed to secure the electrolyte in 45 place, and that the instrumentalities described are merely illustrative of an embodiment of my invention; as applied to an inverted battery cell.

I claim:

1. A dry cell having a perforated bottom, 50 means for supporting said cell in inverted position, in combination with an electrolyte and a detachable cover for holding said electrolyte in place at the perforated bottom of said cell.

2. A dry cell container having a perforated cup-shaped bottom in combination

with an electrolyte located in said cup-shaped bottom, and held in place by a detachable cover.

3. A dry cell having a perforated cup-shaped bottom, in combination with an electrolyte placed in said bottom outside of the cell case, and a detachable cover fitted to the cell case for holding said electrolyte against displacement. 60

4. A dry cell zinc container having a depressed or cup-shaped perforated bottom, in combination with an exciting agent, detachable means for holding the same against displacement at said bottom, and means for 70 supporting said cell in inverted position to allow said agent to percolate through the perforations in said bottom and saturate the cell lining. 75

5. A dry battery cell having a depressed or cup-shaped perforated bottom, in combination with a capsule containing an exciting electrolyte, and detachable means for securing said capsule within said cup-shaped bottom. 80

6. A dry battery cell having a perforated bottom, in combination with detachable means for holding an exciting electrolyte substance against displacement at said bottom, and means for supporting said cell in 85 inverted position to permit said substance to enter said cell through said perforations.

7. In an electrolyte container, a cup-shaped body having a perforated bottom, a cover for said body, said cover having an 90 offset flange for engagement with the bottom of a dry battery cell.

8. In an electrolyte container, a cup-shaped receptacle having a perforated bottom, a cover for said receptacle, said cover 95 having means thereon for detachable engagement with a dry battery cell to hold said container against the bottom thereof.

9. As an article of manufacture, a capsule containing an exciting electrolyte substance, 100 said capsule being adapted to fit the cup-shaped bottom of a dry battery cell, and means for securing said capsule in place upon the bottom of a cell.

10. As an article of manufacture, a capsule containing an exciting electrolyte in compressed tablet form, said capsule having a perforated top and bottom, whereby to give access to water upon immersing the capsule therein, and detachable means for 110 securing said capsule to the bottom of a cell. 105

EARL H. ROLLINSON.
